UNITED STATES PATENT OFFICE

CHARLES H. LYON, OF KENNEBEC, SOUTH DAKOTA

COMBINED COOKING AND HEATING STOVE

Application filed March 15, 1929. Serial No. 347,383.

This invention relates to a cooking and heating stove, and has for its object the production of a stove of the cooking type which can also be used for the purpose of heating, through the employment of two grates, either one of which may be used separately, or both of which may be used at the same time, according to the requirements. It is the purpose of the inventor that one grate be employed in 10 the usual location in a cooking stove near the top or under the stove plates and the other beneath the first and far enough from it to create a space for a second fire.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a view in side elevation 25 of a dual purpose cooker-heater embodying the invention; and

Figure 2 illustrates a front elevation, partly in section.

In these drawings, 5 denotes the oven of an 30 ordinary cooking stove, which may have the usual fire back and air chambers or flues, and as these may be changed to suit particular requirements, the inventor does not wish to be limited with regard to the interior construction of the stove body and the arrangement 35 of the oven with respect thereto.

The space in front of the fire back 6 is divided into what may be termed two fire boxes, one of which is above the upper grate 7 and 40 the other of which is between the lower grate 8 and the upper grate 7, as fully illustrated. The top 9 of the stove and its plates, such as 10, are located approximately the same distance from the grate 7 as in ordinary cooking 45 stoves.

One wall of the stove is preferably formed with two lips or chutes 11 and 12 guarded or closed by doors 13 and 14, respectively, through which fuel may be delivered to the 50 respective fire boxes. One wall of the stove

is also provided with hinged doors, such as 15 and 16, closing openings to the respective fire boxes, through which fuel may also be introduced to the said fire boxes. An ash pit 17 under the lower grate 8 is closed by a door 55 18 in order that access may be had to the said ash pit for removing deposits of ashes.

It will be apparent from an inspection of the drawing and from the foregoing description that fuel may be applied to the grates or 60 the fire boxes thereof from in front of the fire boxes or at the ends thereof and that, as stated, either or both fire boxes may be used when cooking or when heating action is desired. 65

I claim:

A combined cooking and heating stove comprising a stove body having a fire box, grates one above the other and in spaced relation to each other in the fire box, chutes at the front 70 of the stove, each of which communicates with the fire box above one of the grates, an ash pit below the lowermost grate, doors in the stove body at the ends of the grates and at the ash pit, and doors in the stove body in its wall at 75 right angles to the wall having the first mentioned doors.
